TELEPHONE-EXCHANGE SYSTEM.

1,199,788.

Specification of Letters Patent.

Patented Oct. 3, 1916.

Application filed May 24, 1915. Serial No. 29,944.

To all whom it may concern:

Be it known that I, EDWARD E. HINRICHSEN, a citizen of the United States, residing at New York, in the county of New York and State of New York, have invented certain new and useful Improvements in Telephone-Exchange Systems, of which the following is a full, clear, concise, and exact description.

10 This invention relates to telephone exchange systems, and more particularly to such systems of the central energy type.

It is an object of this invention to provide a telephone exchange system in which it is 15 impossible to connect a source of ringing current to a line previously taken for use.

Another object of this invention is to provide a telephone exchange system in which it is impossible to connect an operator's telephone set to a busy line.

Still another object of this invention is the provision of means operated upon connection of any link circuit with a busy line to signal the operator that the link has been 25 connected to a busy line.

In accordance with this invention, there is provided a telephone exchange system comprising link connecting circuits, the talking strands of each of which are normally open. 30 Associated with each end of each link circuit is a relay for closing the normally open talking strands thereof, this relay being controlled by a second relay whose circuit is completed when the appropriate end of the 35 link is connected to an idle line. A third relay associated with the link circuit operates to prevent the operation of the first and second relays if the link is connected to a busy line. In the calling end of the link 40 circuit, the relays coöperate to control the application of a source of ringing current to called lines. Each end of the link circuit is provided with means for signaling the operator whenever either end of the link circuit has been associated with a busy line.

For a more complete understanding of this invention reference should be made to the accompanying drawing wherein is illustrated a telephone exchange system showing 50 one embodiment of the invention and comprising the usual subscribers' stations, A and B, and a cord circuit C, located at a central office, for interconnecting the subscribers' stations. All apparatus is shown in 55 its normal and unactuated condition. Sub-

scriber A, wishing to converse with subscriber B, signals the operator in the usual manner. The operator, answering, inserts the answering plug into a jack of the calling line, causing the operation of relay 5 over a 60 circuit which may be traced from battery 6 through one winding of line relay 7, contact 8 of cutoff relay 9, ring contacts of the jack and plug, contact 10 of relay 11, winding 12 of relay 5, contact 13 of relay 14 and 65 interrupter 15 to ground. Relay 5, in operating, completes a locking circuit for itself and causes the operation of cutoff relay 9 and relay 11. The operating circuit for these relays may be traced from battery 20, 70 through supervisory signal 21, winding of relay 11, locking winding 22 of relay 5, contact 23 thereof, sleeve contacts of the answering plug and jack, and the winding of cutoff relay 9 to ground. Cutoff relay 9 in operating disconnects the line relay 7 from the line, and relay 11 in operating closes normally open contacts in the talking strands of the answering end of the cord circuit. Since subscriber A has initiated the call and 80 the receiver is off the switch hook, supervisory relay 25 will be operated upon the closure of the normally open contacts in the talking strands of the cord. Supervisory relay 25, in operating, causes the operation 85 of listening relay 26 which connects the operator's telephone set across the talking strands of the cord. The resistance of the winding of listening relay 26 is such that this winding shunts supervisory signal 21, 90 thereby preventing its operation. The operator, finding that the wanted line is that of subscriber B, inserts the calling plug into a jack of B's line, causing the operation of relay 30, the energizing and locking circuits 95 for this relay being similar to that hereinbefore traced for relay 5 associated with the answering end of the cord circuit. The operation of relay 30 causes the operation of relays 31, 32 and 33 and supervisory signal 100 34. The circuit including these relays and the signal may be traced from battery 35, through supervisory signal 34, winding of relays 33 and 32, the locking winding and contact 36 of relay 30, sleeve contacts of the 105 calling plug and jack, and the winding of cutoff relay 31 to ground. Cutoff relay 31 in operating disconnects the line relay of B's line from the line. Relay 32 in operating closes normally open contacts in the talking 110

strands of the calling end of the cord circuit. Relay 33 in operating causes the release of listening relay 26, disconnecting the operator's telephone set from the talking strands of the cord, and substitutes for the winding of relay 26 a resistance 37 which shunts supervisory signal 21 which remains effaced. Relay 33 also connects, through the operation of relay 38, a source of ringing current 39 to the called line, the source 39 being connected to the ring strand of the cord circuit back of the normal open contact thereof, and ground being connected to tip strand back of the normal open contact thereof. Relays 40 and 41 coöperate with relay 38, in a manner well understood, to control the disconnection of the source of ringing current 39 from the called line upon the removal of the receiver thereat from the switch hook. As soon as the ringing current is removed from the called line, supervisory relay 45 operates, retiring supervisory signal 34. When the conversation is finished, both A and B restore their respective receivers to the switch hook, causing the release of supervisory relays 23 and 45, whereupon supervisory signals 21 and 34 operate to furnish disconnect signals. Removal of the plugs from the jack permits all apparatus to return to normal condition.

For convenience and simplicity, only one cord circuit has been shown in the drawing. It is to be understood, however, that at each operator's position, there will be located a plurality of cord circuits like that shown in the drawing.

Assuming that subscribers A and B have been connected together for conversation by means of the cord circuit in the manner hereinbefore described, and assuming further that an operator in attempting to listen-in on the conversation inserts the answering plug into another jack of either A or B's line, relay 5 of the second cord circuit will not operate, for the cutoff relays 9 and 31 are both operated, opening the paths from the battery. Due to the presence of the answering plug of the first cord circuit in the jack of A's line and the calling plug thereof in the jack of B's line, the potential of the sleeves of all of the jacks associated with lines A and B throughout the board will be raised. Therefore, when an answering plug of another cord circuit is plugged into a jack associated with A's line, relay 14 of the second cord circuit will be energized over a circuit from battery 20, supervisory signal 21, winding of relay 11, locking winding 22 and contact 23 of relay 5, sleeve contacts of the answering plug and jack, sleeve contacts of the second jack and second answering plug, contact 46 of relay 5 (in the second cord circuit) and the winding of relay 14 of the second cord circuit to ground. The operation of relay 14 in the second cord circuit

causes supervisory signal 21 of the second cord circuit to flash intermittently, signifying to the operator that the second cord circuit has been connected with the line already taken for use. This circuit for this supervisory relay 21 may be traced from battery 20, supervisory signal 21, alternate contact of relay 14 and interrupter 15, to ground. In a like manner, if the answering plug had been connected to a second jack associated with B's line, supervisory signal 21 of the second cord circuit would be flashed intermittently. Since relay 5 of the second cord circuit cannot operate, it is impossible to connect the operator's telephone set with the existing telephone connection. It will be seen, therefore, that by the use of a telephone exchange system embodying the present invention, it is impossible to connect an operator's telephone set to a subscriber's line which had been previously taken for use.

Relays 30 and 47 associated with the calling end of the cord circuit correspond to relays 5 and 14 associated with the answering end, and operate in the same manner. It will be recalled that relay 38, which connects the source of ringing current 39 to the called line, is controlled by relay 30. It will now be shown how it is impossible to connect the source of ringing current to a line already taken for use.

When either the answering or the calling plug of the cord circuit C is inserted in the jack of B's line, the cutoff relay 31 thereof will be operated. Should the operator insert the calling plug of a second cord circuit into another jack associated with B's line, the energizing circuit for relay 30 of the second cord circuit will be open at the contact of the cutoff relay 31. Therefore relay 30 cannot be energized. Also upon the connection of the calling end of the second cord circuit with the second jack associated with B's line, relay 47 of the second cord circuit will be operated over a circuit similar to that hereinbefore traced for relay 14 of a second cord circuit. The operation of relay 47 of the second cord circuit causes the calling supervisory signal 34 of the second cord to flash intermittently, indicating to the operator that the calling end of this second cord has been connected to a line already taken for use.

It is to be noted that if the system is not to be equipped for furnishing a signal to the operator, the interrupter 15 may be dispensed with and this connection run direct to ground.

While a plurality of batteries are shown in the drawing, it is to be understood that a single common battery may be substituted therefor, and such is the usual practice.

What is claimed is:

1. In a telephone exchange system, subscribers' lines terminating at a central office,

- a link circuit thereat for interconnecting said lines, normally open talking strands for said link circuit, a relay energized over a circuit including a portion of one strand 5 of said link upon connection of said link with a line, means independent of substation control for rendering said relay independent of the energizing circuit, and a second relay operating upon energization of 10 said first named relay for closing the talking strands of said link circuit.
2. In a telephone exchange system, subscribers' lines terminating at a central office, a link circuit thereat for interconnecting 15 said lines, normally open talking strands for said link circuit, a relay energized over a circuit including a portion of one strand of said link upon connection of said link with a line, a locking circuit for said relay 20 for rendering said relay independent of the energizing circuit, and a second relay included in the locking circuit and operating upon energization of said first named relay for closing the talking strands of said link 25 circuit.
3. In a telephone exchange system, subscribers' lines terminating at a central office, a link circuit thereat for interconnecting said lines, normally open talking strands 30 and a third strand for said link circuit, a relay energized over a circuit including a portion of a talking strand of said link upon connection of said link with a line, a locking circuit for said relay including a 35 portion of the third strand of said link completed upon energization of said relay, and a second relay operating upon energization of said first named relay for closing the talking strands of said link.
4. In a telephone exchange system, subscribers' lines terminating at a central office, a link circuit thereat for interconnecting said lines, normally open talking strands and a third strand for said link circuit, a 45 relay energized over a circuit including a portion of a talking strand of said link upon connection of said link with a line, a locking circuit for said relay including a portion of the third strand of said link completed upon energization of said relay, and a second relay in the locking circuit of said 50 first named relay operating upon completion of the locking circuit to close the talking strands of said link.
5. In a telephone exchange system, subscribers' lines terminating at a central office, a link circuit thereat for interconnecting said lines, normally open talking strands for said link circuit, electromagnetic mechanism 55 operating when the answering end of said link is connected with a calling line to close the talking strands of said link, an operator's telephone set, a listening relay for including said telephone set in telephonic 60 connection with the calling line, a circuit for said listening relay controlled from the calling substation and closed after the closure of the talking strands of said link, whereby said telephone set is connected with the calling line, and relay mechanism responsive 70 to the connection of the calling end of said link with another line for opening the circuit of said listening relay, thereby disconnecting said telephone set from the line.
6. In a telephone exchange system, a telephone line terminating in a plurality of switching terminals at a central office, a plurality of link circuits thereat having co-operating switching terminals, each link having normally open talking strands, relay 80 mechanism operating when a link circuit is connected with a switching terminal of the line for closing the talking strands of said link and for altering the electrical condition of the switching terminals of the line, a relay 85 associated with each link circuit irresponsive to the original electrical condition of the switching terminals of the line but responsive to the altered electrical condition thereof, said relay of the connected link circuit 90 being rendered inoperative by the operation of said relay mechanism, said relay of a second link circuit operating when the second link is connected with another switching terminal of the line for preventing the 95 operation of said relay mechanism of the second link thereby preventing the closure of the talking strands of the second link.
7. In a telephone exchange system, a telephone line terminating in a plurality of 100 switching terminals at a central office, a plurality of link circuits thereat having co-operating switching terminals, mechanism operating when a link circuit is connected with a switching terminal of the line for 105 altering the electrical condition of the switching terminals thereof, a relay associated with each link circuit irresponsive to the original electrical condition of the switching terminals of the line but responsive to 110 the altered electrical condition thereof, the operation of said mechanism rendering said relay of the connected link inoperative, a signalling device, and interrupter mechanism, said relay of a second link responding to 115 the altered electrical condition of the switching terminals when the second link is connected with another switching terminal of the line for including the interrupter mechanism in circuit with said signalling device to 120 furnish a signal denoting that the second link has been connected to a busy line.
8. In a telephone exchange system, subscribers' lines terminating at a central office, a link circuit thereat for interconnecting said 125 lines, normally open talking strands for said link circuit, a relay associated with the calling end of said link and energized over a portion of a talking strand of said link upon connection of the calling end of said link 130

- with a line, means for rendering said relay independent of the energizing circuit, a second relay operating upon energization of said first-named relay for closing the normal 5 breaks in the talking strands of the said link, a source of ringing current adapted to be connected to one of the talking strands back of the normal break, and a third relay also controlled by said first-named relay for connecting said source to the talking strand of the link.
9. In a telephone exchange system, telephone lines terminating at a central office, a plurality of link circuits thereat for interconnecting said lines, each link circuit having normally open talking strands, a source of ringing current, means for connecting said source to the talking strands back of the breaks therein, and relay mechanism 15 preventing the closure of the talking strands when a link is connected to a line to which another link is already connected, thereby preventing the application of ringing current to a line previously taken for use.
- 20 10. In a telephone exchange system, a telephone line terminating in a plurality of switching terminals at a central office, a plurality of link circuits thereat having co-operating switching terminals, a relay associated with the calling end of each link, said relay operating when the calling end of a link is connected with a switching terminal of the line to alter the electrical condition of the switching terminals of said line, a source 25 of ringing current, and a relay operating upon the energization of the first mentioned relay for connecting said source to said line through the calling end of the link, the first mentioned relay of a second link circuit being irresponsive to the altered electrical condition of said line when a second link is connected with another switching terminal of said line, whereby the application of ringing current to a line previously taken for use is 30 prevented.
- 35 11. In a telephone exchange system, subscribers' lines terminating at a central office, a link circuit thereat for interconnecting said lines, a normally open talking strand in said link circuit, a relay energized upon connection of said link circuit with a line over a circuit including a portion of said strand, a second relay operating upon energization of said first named relay for closing said normally open talking strand, and a local locking circuit independent of substation control for the second relay.
- 40 12. In a telephone exchange system, subscribers' lines terminating at a central office, a link circuit thereat for interconnecting the lines, each link circuit having a normally open talking strand, a relay energized over a circuit including a portion of a talking strand of the link circuit upon connection thereof with a line, a local locking circuit for the 45 relay established upon the energization thereof, and a second relay operating upon the energization of the first-named relay for closing the talking strand of the link circuit.
- 50 13. In a telephone exchange system, subscribers' lines terminating at a central office, a link circuit thereat for interconnecting the lines, each link circuit having a normally open talking strand, a relay energized over a circuit including a portion of a talking strand of the link circuit upon connection thereof with a line, a second relay operating upon the energization of the first-named relay for closing the talking strand of the link circuit, and a local locking circuit independent of substation control for the second relay.
- 55 14. In a telephone exchange system, subscribers' lines terminating at a central office, a link circuit thereat for interconnecting the lines, each link circuit having a normally open talking strand, a relay energized over a circuit including a portion of a talking strand of the link circuit upon connection thereof with a line, a local locking circuit for the relay established upon the energization thereof, and a second relay in the locking circuit operating upon the closure thereof for closing the talking strand of the link circuit.
- 60 15. In a telephone exchange system, subscribers' lines terminating at a central office, a link circuit thereat for interconnecting the lines, each link circuit having a normally open talking strand, relay mechanism responsive to the connection of the link circuit with a calling line for closing the normally open talking strand, an operator's telephone set, a listening relay energized upon the closure of the talking strand for including the operator's telephone set in circuit, and a relay operating upon connection of the other end of the link circuit with a called line for deenergizing the listening relay.
- 65 16. In a telephone exchange system, subscribers' lines terminating at a central office in a plurality of terminals, a plurality of link circuits for interconnecting the lines, each link circuit having a normally open talking strand, a source of ringing current, a relay associated with each link circuit for connecting the source of ringing current with the talking strands thereof, a second relay for each link circuit for closing the talking strand, a third relay for each link circuit operating upon connection of the link with a line for causing the operation of the first and second mentioned relays, and means operating upon connection of the link with the line to prevent the operation of the third relay of another link circuit when connected with the same line.
- 70 17. In a telephone exchange system, subscribers' lines terminating at a central office

- 11 a plurality of terminals, a plurality of link circuits for interconnecting the lines, a source of ringing current, a relay associated with each link circuit for connecting
- 5 the source of ringing current with the talking strands thereof, a second relay for each link circuit operating upon connection of the link with the line for causing the operation of the first-named relay, and means
- 10 operating upon connection of the link with the line to prevent the operation of the second relay of another link circuit when connected with the same line.
18. In a telephone exchange system, sub-
- 15 scribes' lines terminating at a central office in a plurality of terminals, a plurality of link circuits for interconnecting the lines, a source of ringing current, a relay associated with each link circuit for connecting
- 20 the source of ringing current with the talking strands thereof, a second relay for each link circuit operating upon connection of the link with the line for causing the operation of the first-named relay, and a relay
- operating upon connection of the link with the line to prevent the operation of the second relay of another link circuit when connected with the same line.
19. In a telephone exchange system, sub-
- 25 scribes' lines terminating at a central office in a plurality of terminals, a plurality of link circuits for interconnecting the lines, a source of ringing current, a relay associated with each link circuit for connecting the source of ringing current with the talking strands thereof, a second relay for each link circuit operating upon connection of the link with the line for causing the operation of the first-named relay, and a relay
- 30 normally associated with the line circuit
- 35 operating upon connection of the link with the line to prevent the operation of the second relay of another link circuit when connected with the same line.
- In witness whereof, I hereunto subscribe
- 40 my name this 22 day of May A. D., 1915.
- 45

EDWARD E. HINRICHSEN.
